(57) **CLAIM**

The ornamental design for a tea infuser, as shown and described.

DESCRIPTION

FIG. 1 is a perspective view of the tea infuser showing one example of the environment in which the invention may be used, namely affixed to rim of a beverage mug (shown in broken lines);

FIG. 2 is a front of the tea infuser of this design;

FIG. 3 is a right view thereof;

FIG. 4 is a left view thereof;

FIG. 5 is a top view thereof;

FIG. 6 is a rear view thereof;

FIG. 7 is a rear view thereof showing the tea infuser in a partially unfolded manner such that the rear is unclasped; and, FIG. 8 is a front view thereof showing the flat pattern of the tea infuser.

The broken lines in the figures are shown for illustrative purposes only and form no part of the claimed design.
